CLAIM

The ornamental design for a lifting platform as shown and described.

DESCRIPTION

FIG. 1 is a front perspective view of a lifting platform showing our new design;

FIG. 2 is a rear perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof illustrating the lifting platform with environment; and,

FIG. 10 is a bottom perspective view of FIG. 8.

The broken lines immediately adjacent to the claim depict the bounds of the claimed design, while all other broken lines are directed to environment. The broken lines form no part of the claimed design.
